(57) **CLAIM**

(22) Filed: **Jun. 4, 2002**

The ornamental design for a coupling nut for an electrical connector, as shown and described.

(51) LOC (7) Cl. **08-08**

DESCRIPTION

(52) U.S. Cl. **D8/397**

FIG. 1 is a front view of a coupling nut for an electrical connector of the present invention, the back view being identical to the front view;

(58) Field of Search D8/382, 397, 399; 411/81, 98, 103, 106, 145, 146, 172, 179, 197, 204, 248, 337, 338, 368, 371.2, 372.5, 418, 427, 429, 430, 431, 432, 436, 437, 500, 511, 512, 514, 531, 532, 533, 535, 536, 537, 538, 542, 544, 918, 928; 70/229; 301/35.623, 111.01; D13/147

FIG. 2 is a right side view of the coupling nut for an electrical connector of FIG. 1, the left side view being identical to the right side view;

(56) **References Cited**

FIG. 3 is a top view of the coupling nut for an electrical connector of FIG. 1;

U.S. PATENT DOCUMENTS

FIG. 4 is a bottom view of the coupling nut for an electrical connector of FIG. 1; and,
